UNITED STATES PATENT OFFICE.

EDWARD R. GORMAN, OF WEST HAVEN, CONNECTICUT.

SANITARY MOUTHPIECE-PROTECTOR FOR TELEPHONES.

1,172,277.

Specification of Letters Patent. Patented Feb. 22, 1916.

Application filed January 5, 1915. Serial No. 711.

To all whom it may concern:

Be it known that I, EDWARD R. GORMAN, of West Haven, in the town of Orange, in the county of New Haven, in the State of Connecticut, have invented certain new and useful Improvements in Sanitary Mouth-piece-Protectors for Telephones, of which the following is a specification.

My invention relates to a sanitary mouth piece protector for telephones, and it has for its object to provide means for preventing the transmission of disease germs through contact with or proximity to the mouth pieces of telephones.

The invention consists in the novel protector and means for its attachment to the transmitter mouth piece as hereinafter more fully described and claimed.

In the accompanying drawings forming a part of this specification, Figure 1 is a front view of a telephone mouth piece embodying my improved protector. Fig. 2 is a similar view of one of the blanks or sections of which the protector is composed. Fig. 3 is a side view of Fig. 1. Fig. 4 is a central vertical lengthwise section through Fig. 1. Fig. 5 is a front view of the annular base or attaching pad upon which the blanks or sections forming the protector are secured or built up.

Referring to the drawings 10 designates the mouth piece of an ordinary telephone. It is of the usual bell mouthed or outwardly flaring shape, and is provided with the screw threaded hub 11 at its inner end by means of which it can be screwed to the support, here requiring neither to be shown nor described. Across the inner end is extended the usual perforated head or partition 12 also requiring no further description.

My invention comprises essentially a system or series of detachable sections or layers superimposed over one another and fitted to the mouth piece in a manner that permits their being readily removed singly, to provide a clean and uncontaminated surface each time that the telephone is required to be used, and successively presenting a new superficies for each user. In carrying out the invention it is essential that the series of surfaces shall be susceptible of being readily attached to the mouth piece, without the use of tools or the employment of mechanical skill, and an important part of the invention consists in the mechanism by which this result is accomplished. The sani-

tary protector and its means of attachment to the mouth piece of the telephone is described as follows.

An annular piece or base 13 of cardboard or other suitable material is provided of such proportions that it will just freely pass over the end of the mouth piece 10, as indicated in the sectional view in Fig. 4. To the face of this annular part is glued or otherwise securely fastened an annular piece 18 of thinner and pliable material projecting or overlapping upon the area of the hole through the base 13 to a certain extent as clearly shown in Fig. 5, and the internally overlapping portion is slit at short intervals as at the points 14, which provide a fringe of flaps 15 all around the interior edge of the base or annular part 13. Said flaps in operation offer no hindrance to the act of slipping the base upon the mouth piece with the fringe on the following side of the cardboard and therefore in position to allow the flaps to readily swing back therefrom as it advances over the mouth piece, but in the reverse movement, in which the side of the cardboard having the fringe of flaps upon it becomes the advancing or leading part, the flaps will buckle toward the base, and obstruct its removal, effectually preventing its displacement.

To the face of the aforesaid annular base is glued or otherwise suitably attached a series of bell shaped sections 16 superimposed one over another as shown in Fig. 4. They are molded of reentrant shape with respect to the mouth piece, and thus are bent over at their outer part around the edge of the mouth piece, and penetrate within the bell mouthed cavity of the mouthpiece, the outermost section extending nearly to the partition 12. The outermost section is the shortest and extends a comparative short distance into the mouth piece, the next succeeding section extends a trifle farther, so that it overlaps the first a certain amount, and each successive section overlaps the one preceding it, taken in the order from the outer side of the mouth piece inward. By means of this arrangement, it will be seen, that in operation, the innermost layer or section entirely covers all the others, and if removed the same is true of the next section, and of them all. Thus in operation, the removal of a section after the telephone has been used and prior to its repeated use in-

sures a clean surface on the interior of the mouth piece for such succeeding use, and neutralizes the liability to germ transmission by such use.

- 5 The bell mounted configuration of the layers may be easily given to them by molds, using flat paper or similar sheet material for the purpose. Such cup like shape tends to render the built up cone or pad of substantial construction, and prevent the detachment of the layers except as intended. To facilitate the ready detachment of the layers singly, as required, one or more flaps 17 may be provided on the edge of each section, projecting from the circumference thereof as shown in Fig. 2 and folded over toward the center of the cone as shown in Figs. 3 and 4. These flaps by slightly springing above the general surface of the pad, as shown in 20 said figures, may be readily grasped by the thumb and finger, and the layer thus pulled off from the pad without trouble. The removal of one layer exposes the flaps of the next succeeding layer beneath it, which in 25 turn may be detached by this means.
- The outer edges of the sections may simply be glued edgewise to the base abutting against it, by which arrangement they will collectively be held sufficiently securely for 30 transportation, and for being mounted upon the mouth piece, but they will not adhere so tenaciously as to prevent their ready detachment by single pieces by means of the flaps 17 for taking hold of them. As the 35 flaps of only the outermost section is exposed, it therefore is impossible to detach the sections by means of the flaps in series or any way except single layers, one at a time, as called for in use.
- 40 In the use of the protector the possibility of contagion by the inhalation of disease germs deposited upon the mouth piece of the telephone may be prevented by the simple precaution of tearing off the first section 45 or layer of the pad just prior to speaking into the transmitter. As a further preventive, the sections may be treated with

some antiseptic solution which will insure additional protection in the use of the device. After the sections are all used, the 50 base may readily be torn off from the mouth piece and a new pad mounted thereon in its place. The number of sections mounted upon a base, is governed by the thickness of the material, and by the required proportions of the cone, which should in no case be made too bulky or sufficiently thick to obstruct the chamber of the mouth piece in transmitting sound.

I claim and desire to secure by Letters 60 Patent:

1. A sanitary mouth piece protector for telephones comprising in combination a base plate receivable over the edge of the mouth piece and provided with a series of flaps 65 overlapping the orifice through the plate adapted by buckling under to prevent the withdrawal of the plate over and from the edge of the mouth piece, and a series of layers of fabric fitting within each other and 70 the mouth piece having their outer edges secured to the base plate and singly detachable therefrom.

2. A sanitary mouth piece protector for telephones comprising in combination a base 75 plate receivable over the edge of the mouth piece and provided with a series of flaps overlapping the orifice through the plate adapted by buckling under to prevent the withdrawal of the plate over and from the 80 edge of the mouth piece, and a series of layers of fabric fitting within each other and the mouth piece having their outer edges secured to the base plate and singly detachable therefrom and provided with holding 85 flaps by which they may be plucked singly from the plate and the series, substantially as and for the purpose specified.

Signed at New Haven, Connecticut, this second day of January, 1915.

EDWARD R. GORMAN.
